UNITED STATES PATENT OFFICE

109,537

DESIGN FOR A RADIO BAR CABINET

Oscar M. Snead, Newport News, Va.

Application January 27, 1938, Serial No. 74,599

Term of patent 3½ years

To all whom it may concern:

Be it known that I, Oscar M. Snead, a citizen of the United States, residing at Newport News, in the county of Warwick and State of Virginia, have invented a new, original, and ornamental Design for a Radio Bar Cabinet, of which the following is a specification, reference being had to the accompanying drawings, forming part thereof.

Figure 1 is a view in top plan of a radio bar cabinet embodying my design.

Figure 2 is a view in rear elevation.

Figure 3 is a view in front elevation.

Figure 4 is a view in side elevation.

I claim:

The ornamental design for a radio bar cabinet, as shown.

OSCAR M. SNEAD.
